UNITED STATES PATENT OFFICE.

GEORGE P. WIGGINTON, OF KALAMAZOO, MICHIGAN, ASSIGNOR TO KALAMAZOO LOOSE LEAF BINDER COMPANY, OF KALAMAZOO, MICHIGAN.

TEMPORARY BINDER OR LOOSE-SHEET HOLDER.

1,001,489.

Specification of Letters Patent. Patented Aug. 22, 1911.

Application filed December 20, 1910. Serial No. 598,411.

To all whom it may concern:

Be it known that I, GEORGE P. WIGGINTON, a citizen of the United States, residing at Kalamazoo, Michigan, have invented 5 certain new and useful Improvements in Temporary Binders or Loose-Sheet Holders, of which the following is a specification.

This invention relates to improvements in temporary binders or loose sheet holders. 10 My improvements are especially adapted to the type of binder shown in Letters Patent No. 851,276, of April 23, 1907, to Harry F. Bushong, and as I have embodied them in practice in a binder of said type, I so 15 illustrate the same herein.

The main objects of this invention are: First, to provide in a temporary adjustable binder, an improved back strip. Second, to provide in a temporary binder, an improved 20 clamping bar hinge. Third, to provide in a temporary binder, an improved leaf holding or binding strip.

Further objects, and objects relating to structural details will definitely appear 25 from the detailed description to follow.

I accomplish the objects of my invention by the devices and means described in the following specification.

The invention is clearly defined and 30 pointed out in the claims.

A structure which is a preferred embodiment of my invention is clearly illustrated in the accompanying drawing, forming a part of this specification, in which:

35 Figure 1 is a rear view of a structure embodying the features of my invention, the binder being shown open and the rear walls of the cover being broken away to better disclose the mechanism. Fig. 2 is a 40 longitudinal section, the binder being shown closed. Fig. 3 is a detail perspective showing the structural details of the back strip. Fig. 4 is an inside perspective view of one of the clamping bars, the reinforcing strip 15 45 being omitted. Fig. 5 is a perspective view of one of the clamping bar hinge members. Fig. 6 is a rear view of such hinge member. Fig. 7 is a perspective view of a modified 50 construction of the back strip. Fig. 8 is a cross section through one of the binding strips. Fig. 9 is an inside detail plan of one of the binding strips. Fig. 10 is a rear view of the binder closed.

In the drawing, similar reference char-

acters refer to similar parts throughout the 55 several views.

Referring to the drawing, the covers 1 are preferably formed with chambers there- 60 in to receive the adjusting mechanism, and the back strip 2. These chambers are open 60 at the inner ends of the covers. The covers are connected by the binding strips 3, which are connected to one of the covers, as by 65 means of the rivets 4 and connected to the binder adjusting mechanism which is ar- 70 ranged in the other cover. This adjusting mechanism, in the structure illustrated, consists of the screw shaft 5 mounted in suit- 75 able bearings in the covers and adapted to be manipulated, as by means of a key, and the bar 6 on the screw, the mechanism be- 80 ing that shown in the Bushong patent re-ferred to. The binding cords 3 are con- 85 nected to the cross bar 6. The back 2 is connected by means of the elastic straps 7 to one of the covers and by means of the straps 8 to the bar 6, so that the back strip 75 is adjusted by the binder adjusting mecha- 90 nism.

The clamping bars 9 are pivotally mounted 80 on the covers, the connections prefer- 95 ably consisting of the rigid hinge members 10 and the pintles 11 on the clamping bars, the pintles being arranged longitudinally 100 in the bars, as shown in Fig. 4. The clamp- 85 ing bars are slotted to receive the ends of the hinge members 10 and are provided with pintle receiving members having pairs 95 of ears 12 secured together at their rear edges and having laterally-projecting at- 105 taching straps 13, which are secured to the bars at each side of the slots. The ears en- 100 gage the sides of the slots and are sup- 105 ported thereby. These hinge members serve to brace the clamping bars at this 100 point, where they are weakened by slotting to receive the ends of the hinge a.ms. The pintle receiving members are preferably 105 formed of sheet metal. The clamping bars are notched at 14 to receive the binding 100 strips 3. The clamping bars are preferably 105 formed of wood, and further reinforced by the metal strips 15 arranged in grooves 16 105 formed in the inner sides of the bars. (See Fig. 2.) These reinforcing strips are not 105 shown in Fig. 4.

The back strip is provided with a label opening, and preferably with a closure 17

for said opening which forms a pocket for the label 18. The closure piece 17 is secured to the back strip by stitching 19, spaced from the edge of the opening as to form a label-engaging member at each side of the opening. This supports the label so that it can be adjusted longitudinally of the opening to bring it into proper position on the back, as shown in Fig. 10, as the quantity 10 of sheets or leaves in the binder is varied, which varies the position of the back, and consequently the label if fixed thereto.

In Fig. 7 I show a modified form of the label supporting members, the same being 15 formed by attaching strips of thin metal along the longitudinal edges of the opening. These thin metal strips can be stitched in the manner indicated.

I preferably form the binding strips, as 20 shown in Figs. 8 and 9, by folding strips of leather longitudinally so that the edges abut and stitching longitudinally. This forms a strong flat binding strip having curved smooth edges which is not likely to abrade 25 or tear the sheets, as 21. The sheets have T-shaped notches 22 therein adapted to engage these binding strips. By thus forming the strips, they are of considerable size and serve to very effectively keep the sheets in 30 alinement in the binder, and while the strips have sufficient flexibility they are, at the same time, of sufficient rigidity to maintain their position in the opening of the binder.

While I have illustrated my improvements in an embodiment in which I have used them in practice, I am aware that they are capable of considerable variations in details, without departing from my invention, but as such variations will no doubt be obvious to those skilled in the art to which this 40 invention relates, I have not attempted to illustrate or describe the same herein.

Having thus described my invention, what I claim as new and desire to secure by Letters Patent is:

1. The combination with the chambered covers, of binding strips suitably connected to one of the covers; an adjusting mechanism for said binding strips comprising a 50 bar arranged in the other cover; a back strip having a longitudinal label opening therein arranged to telescope into said covers, one end of said back strip being connected to said bar of said adjusting mechanism and the other being suitably connected to the other cover; a closure strip for said label opening 55 stitched on the inner side of said back strip, the stitching being spaced from the edges of the back strip opening to provide longitudinally-disposed label retaining members at each side of said opening; and a label arranged in said opening to slidably engage said retaining members.

2. The combination with the chambered 60 covers, of binding strips suitably connected

to one of the covers; an adjusting mechanism for said binding strips comprising a bar arranged in the other cover; a back strip having a longitudinal label opening therein arranged to telescope into said covers, one end of said back strip being connected to said bar and the other being suitably connected to the other cover; a label; and a pocket arranged to slidably support said label in said opening.

3. The combination with the chambered covers, of binding strips suitably connected to one of the covers; an adjusting mechanism for said binding strips arranged in the other cover; a back strip having a longitudinal label opening therein arranged to telescope into said covers, one end of said back strip being connected to said adjusting mechanism and the other being suitably connected to the other cover; a label; and label retaining members disposed at the edges of said opening whereby said label is supported to be adjusted longitudinally of said back.

4. The combination with the chambered covers, of binding strips suitably connected to one of the covers; an adjusting mechanism for said binding strips comprising a bar arranged in the other cover; a back strip having a longitudinal label opening therein arranged to telescope into said covers, one end of said back strip being connected to said bar and the other being suitably connected to the other cover; a label; and means for supporting said label on said back to permit its being adjusted longitudinally thereof.

5. The combination with the chambered covers, of binding strips suitably connected to one of the covers; an adjusting mechanism for said binding strips arranged in the other cover; a back strip having a longitudinal label opening therein arranged to telescope into said covers, one end of said back strip being connected to said adjusting mechanism and the other being suitably connected to the other cover; a label; and means for supporting said label on said back to permit its being adjusted longitudinally thereof.

6. The combination with the chambered covers, of an adjusting mechanism; a back strip having a longitudinal label opening therein arranged to telescope into said covers; a closure strip for said label opening stitched on the inner side of said back strip, the stitching being spaced from the edges of the back strip opening to provide longitudinally-disposed label retaining members at each side of said opening; and a label arranged in said opening to slidably engage said retaining members.

7. The combination with the chambered covers, of an adjusting mechanism; a back strip having a longitudinal label opening therein; a label; and longitudinally-disposed

label engaging members disposed on the inner side of said back at the edges of said opening whereby said label is slidably supported in said opening.

5 8. The combination with the chambered covers, of an adjusting mechanism; a back strip arranged to telescope into said covers; a label; and means for supporting said label on said back strip arranged to permit the

10 longitudinal adjustment of said label.

9. In a temporary binder, the combination with the covers, of inwardly-projecting rigid hinge members at the inner ends of said covers; clamping bars having slots in

15 their inner sides adapted to receive said hinge members; pintles arranged longitudinally of said bars across said slots; and pintle receiving members arranged in said slots, said pintle members having pairs of ears

20 connected at their rear edges and being provided with laterally-projecting attaching straps, all coacting for the purpose specified.

10. In a temporary binder, the combination with the covers; leaves having T-shaped binding strip openings in their rear edges; and binding strips formed of leather, the edges of the strips being folded inwardly to abut and secured by longitudinal rows of stitches, the edges of said binding strip being curved.

25 11. In a temporary binder, the combination with the covers; leaves having T-shaped binding strip openings in their rear edges; and binding strips formed of leather, the edges of the strips being folded inwardly to abut and secured by longitudinal rows of

30 stitches.

35 In witness whereof, I have hereunto set my hand and seal in the presence of two witnesses.
